THEODORE D. PALMER, OF SYRACUSE, NEW YORK, ASSIGNOR TO T. D. PALMER COMPANY, OF SYRACUSE, NEW YORK, A CORPORATION.

CLOTHES-PRESSING MACHINE.

1,141,900.

Specification of Letters Patent. Patented June 1, 1915.

Application filed May 24, 1910. Serial No. 563,115.

To all whom it may concern:

Be it known that I, THEODORE D. PALMER, of Syracuse, in the county of Onondaga, in the State of New York, have invented 5 new and useful Improvements in Clothes-Pressing Machines, of which the following, taken in connection with the accompanying drawings, is a full, clear, and exact description.

10 This invention relates to certain improvements in clothes pressing machines for pressing garments and other fabrics under direct mechanical and steam pressure, as distinguished from ironing machines having 15 a rolling or sliding motion.

In the class of machines to which this invention appertains the steam is applied to the upper surface of the garment under high pressure varying from ten to sixty pounds 20 per square inch and is confined within predetermined limits by a vertically movable press head having a foraminous presser face which serves the double purpose of additionally pressing the garment by mechanically 25 cal pressure and distributing the steam evenly over the surface of such garment.

The object is to construct and arrange all parts of the machine so as to contribute to the one common result of quickly steaming, pressing and drying the garment in a 30 single operation, thereby materially increasing the total output for a given period of time with a minimum expenditure of labor.

Another object is to combine all of the 35 elements necessary to produce this result in a single machine.

Other objects and uses relating to specific parts of the machine will be brought out in the following description.

40 In the drawings: Figure 1 is a side elevation of a clothes pressing machine embodying the various features of my invention, except that the steam generator is omitted, the press head being shown in its pressing position. Fig. 2 is an enlarged 45 transverse sectional view through the co-acting pressing elements showing the steam dome and superheater together with the valves for controlling the supply of steam 50 to the press head. Fig. 3 is an enlarged top plan of the machine shown in Fig. 1, except that a portion of the table is broken away and portions of the steam dome and steam supply pipe are shown in section.

Fig. 4 is a detail elevation of the locking 55 and releasing mechanism for the movable press head. Fig. 5 is an enlarged detail view of a portion of the oscillatory supporting frame for the press head and adjacent portion of the main frame showing the 60 buffer or limiting stop. Fig. 6 is an inner 65 face view of a portion of the steam dome showing particularly the burner and steam inlet of the dome. Fig. 7 is an enlarged 70 sectional view through the heating chambers on the under side of the buck, the central portion thereof being broken away. Fig. 8 is a top plan of a portion of a modified machine showing the steam supply pipe partly in section and partially inclosed 75 in a steam jacket for keeping the steam which passes through the press head at a maximum temperature.

In carrying out the objects stated, I provide an upright supporting frame —1— 75 with a suitable shelf or table top —2— and arms or brackets —3— extending upwardly from the rear portion of the machine some distance above the table top —2— leaving a clear open space above said top and in front 80 of the arms for the manipulation of the garment to be pressed.

The table top —2— is preferably made of wood secured in a horizontal position, at a convenient height from the floor, to 85 the main supporting frame —1—. Mounted upon the main supporting frame —1— and rising some distance above the top —2— is a bracket —4— to which is secured a horizontally disposed buck —5— for receiving and supporting a garment to be pressed. The base of the buck or garment support, is preferably made of cast metal and provided with central longitudinally extending return steam passages —6— which communicate respectively with a steam supply pipe —7— and an outlet or drain pipe —8—. The pipe —7— leads to a steam generator —9—, Fig. 3, while the drain pipe —8— leads into a suitable catch basin or 90 receptacle —10— which is disposed in a plane some distance below the table top at the rear of the machine and therefore some distance below the buck to allow the water of condensation to gravitate through a pipe 100 —8— into the tank —10—.

The object in passing steam through the passages —6— in the base of the buck —5—

is to heat said buck and thereby aid in quickly drying the garment after being subjected to steam and mechanical pressure.

The drain pipe —8— is provided with a valve —11— which may be closed during the introduction of steam into the passage —6— to prevent circulation thereof, but may be opened at any time to draw off the water of condensation into the tank —10—.

10 A suitable hand pump —12— of special construction, hereinafter described, is employed to return the water from the tank —10— to the boiler and for this purpose is connected by a pipe —13— to the bottom of the tank —10— and is also connected by a pipe —14— to the boiler.

15 The upper surface of the buck is covered with a pad —15— upon which the garments are spread preparatory to pressing, said pad serving to conform to inequalities in the thickness and hardness of different parts of the garment under pressure, thereby preventing mutilation of buttons and similar projections and also preventing excessive pressure upon the parts of unequal thickness.

20 A superposed press head —16— is mounted for vertical movement upon the front end of an oscillatory frame or lever —17— which is journaled or fulcrumed intermediate its ends upon the upper ends of the brackets or arms —3— of the main supporting frame, the rear end of said lever being extended a considerable distance beyond the fulcrum and is provided with longitudinally adjustable counterweights —18— for retracting or returning the head to its normal up-position away from the buck —5—.

25 This presser head may be rocked to its pressing position by means of a hand lever —19— where it is held and additionally depressed by means of a pedal lever —20— which is fulcrumed at —21— near the rear end of the machine a considerable distance below the table top —2—, the rear end of said pedal lever being provided with an upright pawl —22— having a shoulder —23— movable into and out of operative engagement with a roller abutment —24— on the rear end of the oscillatory frame —17—, said pawl being forced into operative engagement with said abutment by means of a spring —25—, as best seen in Fig. 1.

30 The function of the pedal lever —20— and pawl —22— is to depress the head with greater force upon the garment after the head has been lowered by the hand piece —19— to its initial pressing position or sufficient to permit the shoulder —23— of the pawl —22— to ride under the abutment —24—.

35 The front arm of the lever —20— to which the pedal is attached is considerably longer than the rear arm upon which the pawl —22— is mounted, thereby permitting

the operator to force the press head downward with a considerably greater pressure than that of the steam, the expansive force of which tends to force the head upward away from the buck.

40 When the pressing operation is completed the pawl —22— is tripped from holding engagement with the shoulder —24— by means of a tripping pawl —26— which is fulcrumed at —27— upon the rear end of the rocking support —17— and is forced to its tripping position against the action of a retracting spring —28— by an operating bar —29—, the latter extending forwardly from the tripping pawl —26— to a point directly over and near the front of the presser head —16— where it is provided with an operating handle —30—.

45 As soon as the pawl —22— is tripped in the manner just described, the presser head —16— is returned to its normal up-position by the counterweights —18—, while the pedal lever —20— is similarly returned to its normal up-position by a retracting spring —31—, as best seen in Fig. 1.

50 The buck —5— and press head —16— are of substantially the same contour in top plan being preferably tapered toward one end.

55 The press head —16— preferably comprises a cast metal body or plate —33— and opposite plates —34— and —35— secured respectively to the bottom and top of the main body in such manner as to form intervening lower and upper chambers —36— and —37—.

60 The bottom plate —34— is foraminous or perforated throughout the greater portion of its area to permit the passage of steam therethrough from the chamber —36— and is covered across its underside by a fabric press cloth —38— which is clamped to the marginal edges of the main body —33— by suitable straps or bands —39— and serves to more evenly distribute the steam over the surface of the garment under pressure and to prevent impressions of the perforations on such surface.

65 The chambers —36— and —37— are entirely separated from each other by the interposed main body —33—, the chamber —36— serving to receive the steam which is to be applied to the surface of the garment, while the chamber —37— also serves to receive steam for the purpose of heating the head.

70 Steam is taken from the boiler —9— through a pipe —40— having a stuffing box —41— coaxial with the axis of movement of the rocking frame —17— and journaled in this stuffing box is one end of a steam pipe extension —42— forming a continuation of the pipe —40— and leading to a superheating steam dome —43—. This dome is mounted upon the top of the press head —16— at the rear thereof and is provided with return

passages —44— extending from end to end of the dome and connected at the end opposite to that to which the supply pipe —42— is connected. This pipe —42— is connected to one end of the return passage, while the opposite end of said passage is connected by a pipe —45— to the center portion of the steam chamber —36— just above an underlying baffle plate —46— which serves to deflect the steam more evenly throughout the area of the chamber —36— and across the upper surface of the perforated press plate —34—, said pipe —45— being provided with a normally closed valve —48— having a hand lever —49— by which it may be opened temporarily by the operator during the pressing operation.

The dome —43— is provided with a heating chamber lying directly under the passages —44— and in which is located a gas burner —50— having its flame directed against the under side of the passages —44— for the purpose of superheating the steam just prior to its entrance to the chamber —36— of the press head.

The supply pipe —45— is provided with a branch —51— leading to the chamber —37— and provided with a valve —52— for controlling the entrance of steam to said chamber for the purpose of additionally and uniformly heating the press head.

It is evident from the foregoing description that the press head may be heated effectively by the introduction of the superheated steam into the chamber —37— without directing the steam to the garment for dry pressing, the heat of the head also serving to expedite the drying of the garment when steam is employed during the pressing operation.

Gas fuel may be supplied to the burner —50— from any available source through a flexible supply pipe —54—, the heating chamber —50— being provided with a venting tilating pipe —55— extending centrally through the upper portion of the dome —43—.

The chamber —37— is connected at one end by a drain pipe —60— to a stuffing box —61— coaxial with the axis of the swinging frame —17— and secured to one of the brackets —3— opposite to that to which the stuffing box —41— is secured, so as to permit rocking movement of the press head. This drainage pipe —60— is continued by a branch —62— to intersect with the drainage pipe —8—, so as to allow the water of condensation from the chamber —37— to flow back into the reservoir or tank —10—, or by opening a valve —63— communicating with an extension —64— this drainage may be carried back to the boiler to which the extension —64— is connected.

The pump —12— may be of any suitable construction for forcibly returning the

water from the tank —10— to the boiler to maintain the proper amount of water in said boiler which water may be converted into steam by any desired form of burner, not necessary to herein illustrate or describe.

The garment or fabric to be pressed is smoothed out upon the upper surface of the pad —15— of the buck —5— after which the press head —16—, which is normally elevated some distance above the buck is drawn down by means of the handle —19— against the action of the counterweights —18— until the pawl —22— is forced into operative engagement with the roller bearing —24— by the spring —25— at which time the head —16— is in close proximity to the surface of the garment to be pressed. The pedal lever —20— is then operated to force the press head against the garment with greater pressure.

The steam in the boiler is maintained under comparatively high pressure and is passed through the superheater 43 where its temperature and expansive force is increased, thereby reducing the moisture after which the high temperature vapor is conducted into chamber 37 by opening the valve —52— for the purpose of heating the press head. This steam pressure is maintained in the chamber 37 at all times while the machine is in use.

During the pressing operation steam may be admitted to the chamber —36— and thence to the surface of the garment through the perforated plate by simply opening the valve —48— by means of the lever —49—. This steam is confined by and within the area of the presser face of the press head when the latter is in its pressing position and serves the double purpose of softening the upper surface of the garment without saturating the entire garment, and also exerting a uniform steam pressure over the entire underlying surface of such garment, so that the garment may be pressed both by mechanical pressure and by steam pressure or by mechanical pressure alone.

By confining the application of the steam to the upper surface of the garment while under mechanical pressure, it is clear that when the press head is raised the steam will escape rapidly from such surface and thereby produce a rapid drying of the garment.

It is also clearly apparent that by heating the entire head by superheated steam in the chamber 37 such heat is imparted to the garment and not only prevents condensation during the pressing operation, but also accelerates the escape of the steam from and consequent drying of the garment when the mechanical pressure is relieved.

In the construction shown in Fig. 8, the maximum temperature of the live steam which is applied to the surface of the garment is maintained by surrounding a con-

siderable portion of the main supply pipe, as —70—, adjacent to the head with a steam receiving jacket —71— to which steam is supplied from the pipe —70— through apertures —72—, the pipe —70— communicating at one end with the main pipe —40—. Steam is also supplied to the upper chamber —37— through the branch pipe —51— which is connected to the steam jacket —71— by a pipe —73—.

10 The steam under high pressure is maintained in the jacket —71— so as to envelop the inclosed portion of the supply pipe —70— which leads to the chamber —36—, thereby maintaining a maximum temperature of the steam nearly at the point where it is applied to the garment, said jacket being used as a substitute for superheating the steam.

15 20 What I claim is:

1. In a clothes pressing machine, two pressing elements connected for direct pressure, one of the pressing elements having two disconnected steam chambers, and 25 means for supplying steam to each of said chambers independently of the other chamber, one of the chambers having a foraminous side forming a presser plate.

2. In a clothes pressing machine, two 30 pressing elements connected for direct pressure, one of the pressing elements having two disconnected steam chambers, means for supplying steam to each of said chambers independently of the other chamber, one of 35 the chambers having a foraminous side forming a pressure plate, and means for superheating the steam in transit to said chambers.

3. In a clothes pressing machine, two 40 pressing elements of substantially the same length and width arranged one above the other and of considerably greater length than width, the upper pressing element being provided with non-communicating steam 45 chambers having separate steam inlets and separate devices operable at will for controlling the passage of steam through said inlets, one of the chambers having a perforated press plate forming the bottom thereof, 50 of, a fabric press cloth secured to said upper pressing element and extending across the underside of the perforated press plate, a drain pipe leading from the other chamber, and means for moving the upper pressing 55 element toward and from the lower element.

4. In a clothes pressing machine, a buck 60 for supporting the garment to be pressed, an oscillatory supporting frame fulcrumed intermediate its ends and having its front end provided with a press head movable toward and from the buck, a counter-weight mounted upon and adjustable along the rear end of the frame toward and from the fulcrum, a handle on the press head for rocking it down against the action of the counter-

weight, a pedal lever, a pawl having its lower end pivoted to the pedal lever and its upper end provided with a shoulder movable into and out of locking engagement with a portion of the oscillatory frame, and 70 means operable at will for forcing the part from its holding position.

5. In a clothes pressing machine a supporting buck for the garment to be pressed, a superposed press head having separate 75 steam chambers located one above the other, the lower chamber being provided with a foraminous bottom forming a presser plate, a steam supply pipe leading to the lower chamber and provided with a valve, a branch 80 pipe leading from said supply pipe to the upper chamber and also provided with a valve, and means for superheating the steam in transit to said chambers.

6. In a clothes pressing machine, a supporting buck for the garment; a superposed press head movable toward and from the buck; said buck and press head each provided with a steam heating chamber; said press head provided with an additional 90 steam chamber; a foraminous presser plate forming one side of said additional steam chamber; a steam generator; steam supply pipes leading from the generator to each of said steam chambers; a drainage tank; drain 95 pipes leading from said steam heating chambers to said tank; and a pump for returning the water from the drainage tank to the generator.

7. In a clothes pressing machine, a supporting buck for the garment to be pressed; a superposed press head movable toward and from the buck; said press head provided with a steam chamber adapted to receive hot steam for heating the head; a means for 100 conveying steam to said steam chamber; said press head provided with a second steam chamber independent of and non-communicating with the other chamber in said head; a perforated plate forming one 105 side of said second steam chamber; means for conveying steam under pressure thereto; and means for causing the steam delivered thereto to be diffused therein.

8. In a clothes pressing machine, a press 110 head; a buck for supporting the garment to be pressed; the said press head having an unobstructed steam chamber adapted to receive, permit of the expansion of and retain hot steam for heating the head; a second 115 steam chamber having a foraminous presser plate forming one side thereof; a means for conveying steam under pressure thereto; and means for exerting mechanical pressure on said press head to force the same in contact with the buck, substantially as described.

9. A clothes pressing machine, comprising a table; a buck for supporting the clothes; a head support pivotally mounted above said

table; a pressing head carried by the forward end of said pivoted head support; means for automatically raising the pressing head; a power lever below the table; a vertical pressure bar pivoted at its lower end to said power lever, the upper portion of said pressure bar having a recess in its edge forming a shoulder thereat; an abutment carried by said head support to be engaged by said shoulder of said pressure bar; a spring connected to the pressure bar for operating it; and a trip lever for disengaging said shoulder from said abutment.

10. In a clothes pressing machine, a buck 15 for supporting the garment to be pressed; an oscillatory supporting frame journaled intermediate its ends and having its front

end provided with a press head movable toward and from the buck; means for automatically raising the press head; a power 20 lever below the table; a vertical pressure bar pivoted at its lower end to said power lever, the upper end of said pressure bar having a recess in its edge forming a shoulder thereat; the frame having an abutment to be engaged by the shoulder of said pressure bar; and a spring connected to the pressure bar for operating it.

In witness whereof I have hereunto set my hand on this 12th day of May 1910.

THEODORE D. PALMER.
